GRINDING COMPANY, A CORPORATION OF MASSACHUSETTS.

STEADY-REST.

1,295,286.

Specification of Letters Patent. Patented Feb. 25, 1919.

Application filed August 13, 1917. Serial No. 186,004.

To all whom it may concern:

Be it known that I, HOWARD W. DUNBAR, a citizen of the United States of America, residing at Worcester, in the county of 5 Worcester and State of Massachusetts, have invented certain new and useful Improvements in Steady-Rests, of which the following is a full, clear, and exact specification.

My invention relates to work supports and 10 more particularly to steady rests for supporting rotating work whose surface is being ground, turned or otherwise formed into a cylindrical shape.

In the art of forming cylindrical surfaces, 15 such as pins or bearings for crankshafts, it is often necessary to support the rotating work against the action of gravity and the pressure of the grinding wheel or other forming tool and to overcome the various detrimental effects due to warping, sagging, vibration or an out of balance condition of the work. Since grinding, as well as other similar operations, to be duplicated, must be carried on with a fine degree of accuracy, great 20 care is necessary to move a steady rest back and forth to allow replacement of the work and to position the rest correctly with reference to the work; hence a fine motion device is necessary for such adjustments. Many 25 types of work such as that of grinding crankshafts require not only fine adjustments but frequent changing of the article being treated; hence, in such cases involving a large number of short successive grinding 30 operations, there results a considerable waste of the operator's time if he is obliged to move the steady rest toward and from the work by means of the slowly actuated mechanism heretofore provided for that purpose.

It is accordingly an object of my invention to provide a simple, easily actuated steady rest, capable of supporting work correctly, with fine precision means for adjusting the rest into exact relation to the work, 45 and with coarse adjustment means for releasing the fine adjustment means and for quickly moving the rest away from the work or toward it to a point where fine motion is required.

With this and other objects in view, as will appear from the disclosure herein set forth, my invention resides in the combinations of parts described in the specification and covered by the claims appended hereto.

In the drawings, in which like reference characters indicate like parts:

Fig. 1 is a vertical elevation partly in section of a steady rest embodying my invention;

Fig. 2 is an enlarged sectional detail of the horizontal adjustments of Fig. 1, parts being shown in perspective;

Fig. 3 is a section on the line 3—3 of Fig. 2;

Fig. 4 is a top plan view of the quick-acting nut shown in Fig. 2.

In the practice of my invention, I have provided a steadyng work-holder adapted to bear against and support rotating work, which is accurately adjustable toward and from the work by means of a fine motion mechanism and which may be quickly and roughly positioned with reference to the work by releasing the fine motion mechanism from operative relation thereto and manually or automatically moving the rest to the desired location.

As a specific embodiment of one phase of my invention, as applied to the grinding art, the construction illustrated may be utilized for steadyng work being ground. It is, however, obvious that similar constructions within the scope of my invention may be utilized in other arts for steady rests to support work being rotatively treated by various methods. Referring to Fig. 1, the steady rest may comprise a shoe-holder 10 supported by and movable relative to a body or stand 11, fastened to a suitable part of a grinding machine 12. Rigidly fixed between a shoulder 13 on the shoe holder 10 and a clamp 14 bolted to the holder is a work supporting shoe 15, which, in the present form, has two spaced bearing surfaces 16 and 17 adapted to engage the work 18 in any desired angular relation to the work grinding axis of rotation,—the surface 16, as illustrated, being preferably located slightly be-

low the horizontal diameter of the work opposite the side being ground,—the other, 17, beneath the work and in the rear of a vertical diameter.

- 5 To adjust the position of the bearing block or shoe 15 relative to the work, I provide means for moving the shoe holder both vertically and horizontally or substantially in the direction of thrust of the work against 10 each contact surface on the steady rest. As illustrated, the stand 11 comprises an L-shaped portion 20 having a circumferential flange 21 on one arm, projecting forwardly and telescoping within a rearwardly extending hollow body portion 22 on the shoe holder, thereby furnishing an interior space 15 for the holder supporting mechanism, which is protected from the entrance of a material amount of water by the overhanging flange 20 23 of the holder.

One of the steadyng work holder supports consists in the present embodiment of a roller 24, riding on the track or roll bearing plate 25 fixed on the stand 11. The 25 roller 24 is rotatably mounted on a pin 26, between the two lugs 27 on a swinging arm 28, which in turn is hinged to lugs 29 on the holder, whereby the latter may be adjusted upwardly relative to the track 25.

- 30 Resting on the top curved surface 30 of arm 28 is the head 31 of a bolt 32 connected to the holder and adapted to serve as one support for the shoe and to furnish a vertical adjustment, as explained below. The 35 surface 30 may have a radius equal to its distance from the center of pin 26 as illustrated.

The other support for the holder and shoe comprises a substantially vertical adjustment link 33 pivotally connected to the lug 34 on the stand and lugs 35 on the shoe holder and permitting backward and forward motions of the holder on its roller track. Fastened to the same stud 36, which 45 attaches link 33 to lugs 35, is another link 37, connecting the holder 10 with the longitudinally movable bolt 38, which is horizontally positioned in the stand 11 and serves as part of the adjusting means. A 50 projecting lug 39 on link 33 may be provided to engage the stand 11 and thereby limit the forward motion of the shoe holder.

In order that the work holder and its shoe may be quickly moved to a desired position 55 and then finely adjusted against the work, I have provided a special mechanism comprising a particular feature of my invention. In its preferred form, this involves a screw threaded adjustment member connected to the holder and movably held relative to the stand by a releasable two part 60 clamping nut, which may be rotated to move the adjustment member and holder with a slow, fine, accurate motion, or which may be

released from operative engagement there- 65 with so that the adjustment member may be quickly and easily brought to a new position.

Except as hereinafter explained, the two adjustment mechanisms are similar in construction and only that shown in Fig. 2 for the horizontal adjustment will be described in detail. The adjustment bolt 38 is slidably mounted in a projecting cylindrically shaped arm 41 of the stand 11 and is keyed thereto, to prevent rotation, but permitting longitudinal adjustment, by means of a set screw 42 in the arm engaging a long groove 43 in the bolt. Rotatably fastened to arm 41 is a nut bearing casing 44 having a constricted neck portion 45 with an annular flange 46. Two semi-circular pieces in this neck constitute a thrust collar 47, which is immovably held, relative to the body 11, by means of a set screw 48, thereby permitting rotative but not longitudinal motion of the casing 44.

The bolt 38 is longitudinally slidable through the casing 44 and the stand 11, to cause horizontal motion of the shoe holder, and is actuated by means of my special two-part clamping nut provided for that purpose. This nut comprises two separated half-nuts 51 and 52 having projecting lugs 53 hinged together by means of a pin 54 on each side of the nut, these pins passing through casing 44 and causing the nut and casing to rotate together and preventing longitudinal movement of the clamping nut. The inner portion of the clamping nut comprises a substantially conically shaped jaw fitting within the hollow casing 44 and having inner threads 56 adapted to engage cooperatively with the screw threads 57 on bolt 38. The outer ends of the nut comprise flaring, flanged, separated portions 58 serving as a handle for turning the nut, or, by pressing them toward each other, for releasing the clamping jaws from engagement with the bolt. Sufficient opening of the nut 110 jaws to provide clearance between nut and bolt is permitted, because of the conically shaped jaws being normally separated considerably from the inner inclosing walls.

As shown, the outer body portion of the 115 clamping nut may be larger in diameter than casing 44 and have an annular flange portion 59 projecting over the casing to aid in keeping undesirable foreign bodies from the interior of the nut.

120 Springs 61 within casing 44 serve to hold the jaws 51 and 52 normally in engagement with the bolt thread. To cause the bolt and jaws to engage each other firmly when brought into contact, I prefer to make the 125 threads of the bolt, buttressed, as illustrated, with a substantially vertical shoulder 62 facing outwardly, and the threads of the

- nut corresponding therewith having their vertical shoulder facing inwardly, the other side of each thread comprising a gradual bevel. This construction is such as to 5 counteract the tendency for the weight of the holder or the thrust of the work to force the clamp nut jaws open and prematurely release the steady rest from its engagement with the work.
- 10 Coöoperating with each clamping nut is a locking or set nut 64 threaded on the bolt and, comprising, in this embodiment, a U-shaped member having a bolt 65 threaded through one arm at one side of the main 15 threaded perforation for engagement with the other arm to draw the arms closer and cause frictional engagement of the threads of nut 64 and bolt 38. A shoulder 66 on the lock nut is adapted to engage a set screw 67 within the hollow flanged outer end of one 20 of the nut portions 51 and thereby limit the inward motion of the bolt.
- In the vertical adjustment mechanism, the 25 casing 44 is similarly rotatably mounted on the holder 10 and the clamping nut is fastened to the casing, the downward pull of the weight of the holder on the bolt 32 maintaining the holder in a definite relation to the stand, depending on the relative position 30 of bolt 32 and the clamping nut. To counterbalance the downward pull due to the weight of the shoe and to insure quick and easy action in roughly adjusting the steady rest into contact with the work, I 35 may provide the vertical adjustment bolt 32 with a concentric helical compressed spring 70 between the bolt head 31 and a shoulder 71 in a circular groove on the under side of the holder 10. This spring is preferably 40 strong enough to lift the work holder, so that it may serve as an automatic means for moving the holder when the clamp nut is released. While the other bolt adjustment member may be provided with a similar 45 spring, I find that this may be omitted, as illustrated.
- To clamp the steady rest to the work 50 table I may provide the latter with an undercut shoulder 75 engageable by a clamp arm 76, on the member 77 pivoted to the stand 11. The clamp arm is actuated by a link 78 connected to a handle 79 pivoted to the stand 11, the link 78 and handle pivots being out of alinement, whereby, as illustrated, upward motion on the handle releases the clamp and downward motion 55 alines the pivots and locks the clamp. Obviously, any suitable and desired type of clamp may be utilized for this purpose.
- 60 The operation of my device, which is apparent from the foregoing disclosure, is as follows:
- After the work 18 has been located in 65 grinding relation to the grinding wheel and the steady rest has been properly positioned 65 opposite the surface to be ground, the operator may release both half nuts from engagement with the adjusting bolts, whereupon the spring 70 tends to lift the lower shoe into contact with the work. The operator then moves the shoe holder by means of the upper clamp nut, while maintaining the nuts' handles pressed inwardly, to locate both shoes in approximately a correct position. In normal use, the steady rest 70 is ordinarily moved but a slight distance to release the work; so that when a new part to be ground has been positioned, it is merely necessary to compress both clamp nuts, whereupon the lower shoe automatically 75 rises, and traveling along the under front side of the cylindrical surface, draws the rest forward until the other shoe is also in contact with the work. Upon releasing the clamp nuts, which resume operative contact 80 with the threaded bolts because of the action of the spring 61, the nuts may be individually turned on the bolts to adjust the shoe bearing surfaces in place with fine precision.
- The set or locking nut 64 may then be 85 brought up and clamped in position abutting against the stop 67, whereby in further use of the steady rest for duplicate grinding operations, the adjusting nuts may be quickly screwed into correct supporting relation to the work without the necessity for extreme care on the part of the operator. Also a micrometer adjustment may be obtained by setting the clamp nut shoulder 66 at a definite angle relative to the stop 67, 90 so that by turning the clamp nut until the shoulder strikes the stop, a predetermined, fine adjustment of the rest is made. As the grinding operation proceeds the position of the shoe may be adjusted, if desired. To remove the work, the clamping nuts are 95 released and the shoe holder quickly moved downwardly and horizontally in a single operation. It is therefore seen that a material saving of many seconds of time for 100 each movement of the shoe holder is made, which results in the course of a day in a considerable economy of time and an increased output, where such articles as crankshafts, requiring but little grinding, are being treated.
- Having thus described my invention, what I claim and desire to secure by Letters Patent is:
1. In a steady rest, a work holder adapted 110 to engage the surface of rotating work, a support for the work holder and means permitting movement of the holder for a quick, coarse positioning thereof to any one of various positions relative to the work axis 115 and for then effecting a fine precision adjustment to the required degree of pressure to steady the rotating body.

2. In a steady rest, a work holder, a support therefor, fine precision mechanism for accurately positioning said holder relative to the work and means for releasing said fine precision mechanism from its operative relation to said holder irrespective of the relative positions of the parts and permitting manual movement of the holder toward the work for a quick, coarse adjustment thereof in any one of various locations relative to the work axis, said mechanism being thereafter operable to position the holder accurately.
3. In a steady rest for a rotating body, the combination of a stand, a work-holder carried thereby and adapted to contact with said body, a slow motion device for adjusting said holder relative to the stand, and means for releasing said slow motion device from operative relationship with the holder and permitting the latter to be moved quickly toward or from the work.
4. In a steady rest, a stand adapted to be fixedly positioned relative to the work to be steadied, a work-holder movably mounted on said stand, an adjusting member connected with the holder and fine motion mechanism supported by the stand and removably clamped to the adjusting member to position the holder accurately relative to the work, said mechanism being releasable from operative relation with the adjusting member to permit quick relative movement of the parts to substantially the desired position, whereupon a fine adjustment may be made by means of said fine motion mechanism.
5. In a steady rest, a support, a work holder adapted to engage the surface of a rotating work and means for effecting a fine adjustment of the position of the holder, comprising a threaded rod and a clamping nut movable relative to each other, one of which connects with the holder and the other with the support, said clamping nut being releasable from the rod to permit a quick, coarse adjustment of the holder.
6. In a steady rest, the combination of two relatively movable members, one adapted to support work being treated, a threaded adjustment rod rotatably and longitudinally immovable relative to one member, and a releasable, threaded clamping nut engaging said rod and rotatively movable but longitudinally immovable relative to the other member, whereby said nut may cooperate with said rod and serve as a fine motion mechanism for moving the work supporting member or may be released therefrom to permit a quick adjustment of the relatively movable parts.
7. In a steady rest, an adjustable work holder adapted to engage work to be steadied, a stand carrying said holder, a screw-threaded bolt non-rotatably connected with said holder for moving the same, an internally threaded member rotatably supported by the stand and adapted to coöperate with said bolt to move the holder with a fine motion, and means for instantly disengaging said member and bolt irrespective of their relative positions to permit rapid relative movement of these parts.
8. In a steady rest, the combination of a stand, a work-holder, means for supporting said holder movably on the stand, a threaded adjustment member connected with the holder, means for holding said member rotatively but not longitudinally immovable relative to the stand, and a clamping nut rotatably carried by the stand and coöperatively engaging the adjustment member to move the same with a fine, accurate motion, said nut being releasable from said member for a coarse adjustment of the holder.
9. In a steady rest, the combination with a supporting stand and a work-holder movable relative thereto, of a longitudinally movable but non-rotative screw threaded adjusting member connected with the work-holder, a screw threaded clamping device adapted to coöperate rotatively with the adjusting member to move the holder with a fine accurate motion, means for quickly releasing the threaded parts from operative engagement with each other and means for automatically moving said holder relative to the stand when the parts are released.
10. In a steady rest, the combination with a stand and a work-holder movably mounted thereon, of means for adjusting said holder vertically relative to the stand, comprising a rotatively immovable threaded member supported by the stand, a threaded clamping nut coöperatively engaging the threaded member and rotatably fastened to and supporting the holder, whereby the latter may have a fine motion adjustment by rotation of the clamping nut, and means for releasing the clamping nut from engagement with the threaded member to permit longitudinal, non-rotatable relative movement of nut and member for a quick, coarse adjustment of the position of the holder.
11. In a steady rest, a stand, a work-holder movably supported thereon, a threaded adjustment member non-rotatably connected with the holder, a rotatable clamping nut comprising two threaded half-nuts hinged together, resilient means causing said nut normally to engage said member, and means whereby rotation of said nut will move said member and holder with a fine motion, said half-nuts having means, including handles, for releasing them from operative engagement with said member to permit rapid movement of the holder.

12. In a steady rest for supporting rotat-
ing work, the combination with a stand and
a work holder movable relative thereto, of
a screw threaded member operatively en-
gaging one of said parts, a releasable and
5 rotatable clamp nut coöperating with the
other part for adjusting the position of the
holder, said member and clamp nut having
buttressed threads adapted to prevent disen-
gagement thereof due to pressure of the 10
work.

Signed at Worcester, Massachusetts, this
10th day of August, 1917.

HOWARD W. DUNBAR.
